UNITED STATES PATENT OFFICE.

HENRY B. FOULDER, OF GLENBROOK, CONNECTICUT, ASSIGNOR TO J. P. CURRY MFG. CO., INC., OF STAMFORD, CONNECTICUT, A CORPORATION OF NEW YORK.

APPARATUS FOR STRINGING WIRE TIES.

Application filed November 7, 1922. Serial No. 599,547.

This invention relates to machines for stringing together wire ties.

stringing of articles in this manner facilitates their being counted at any time. 55

So far as applicant is aware no method of nor machine for stringing stub-nosed 5 wire ties has been devised heretofore. Therefore, such ties have been packed and shipped loose, with the result that they readily become tangled together, and much annoyance and loss of time and ties is occasioned in untangling the ties when they are 10 wanted for use.

In order that a clearer understanding of my invention may be had, attention is hereby directed to the accompanying drawings, forming a part of this application and illustrating one possible embodiment of my invention. Referring to the drawings, Fig. 1 is a diagrammatical top plan view of a portion of a tie-making machine with a tie-stringing attachment embodying my invention 60 associated therewith; Fig. 2 is a vertical longitudinal sectional view taken on the line 2—2 of Fig. 1; Fig. 3 is a vertical longitudinal sectional view taken on the line 3—3 of Fig. 1; Fig. 4 is a vertical longitudinal sectional view taken on the line 4—4 of Fig. 1; and Fig. 5 is a vertical transverse sectional view taken on the line 5—5 of Fig. 1. Similar reference characters refer to similar parts throughout the several views of the 65 drawings.

The object of my invention is to provide a machine for stringing articles, such as stub-nosed wire ties, so that they may be 15 packed and shipped without danger of becoming tangled together, and so that each article may be readily and easily separated from the others when wanted for use. A further object of my invention is to provide 20 a stringing machine for stub-nosed wire ties which may be used as an attachment for a usual tie-making machine. Other objects will be in part obvious and in part pointed out hereinafter.

Referring to the drawings, the tie-making machine 1 is of well known construction. The machine operates to draw wire 2 from a spool (not shown) into the machine where 80 a suitable length 3 is cut off by cutter 4, which length is then advanced to another place, as 5, where stub ends are formed on the tie by punching members 6. From here the tie is advanced forwardly by the machine so that usually it will slide down inclines 7 into a suitable box or receptacle. The forward feed of the ties is effected by means of a notched pivoted lever 8 cooperating with a reciprocating tie carrier 9. The 85 above construction is well known. 90

25 In accordance with my invention, I arrange the stringing machine to catch each article, such as a completed stub-nosed tie, as it is delivered thereto, as by a tie-making machine. Means are provided for holding 30 each article in a certain place until mechanism of the stringing attachment has crossed two strings or other binding material behind it, near each end, after which the mechanism is arranged to bring another article into 35 place and to push the preceding article ahead, the strings then crossing behind the succeeding article near each end but in a reverse manner to the previous crossing. Thus each of the four strings is woven alternately over and under successive articles, and at each end when one string goes over 40 an article the other string will go under the article, and vice versa. Means may be provided for running the stringing attachment 45 in synchronism with a delivering machine, such as a tie-making machine, and the effect is to weave the articles, as they are delivered from the delivering machine, into an extended ladder-like strip. Articles so bound 50 together are very convenient to pack and ship, are in no danger of becoming tangled together, and when desired for use, the articles may be very readily and easily unstrung from the ladder one after another. The

The stringing attachment 10 is placed close to the discharge end of tie-making machine 1, having two spaced brackets or arms 11, so located that instead of the completed ties sliding down inclines 7 the tie carrier 9 of the tie-making machine slides each tie to a certain place 12 upon arms 11. A notched extension piece 13 is preferably attached to the front of the usual tie carrier 9, as by screws 14, which operates to advance each tie two further steps upon the reciprocation of carrier 9, the final place of depositing the tie being the place where its stringing is to be accomplished. The stringing attachment provides means for preventing the backward movement of the ties when carrier 9 moves back. To this end on each 100 105

side of the stringer adjacent sides 15 of carrier extension 9 is a plate 16, each mounted on a frame member 17 of the stringer, by means of a screw 18 penetrating a slot 19 in the plate, to slide up and down, each plate being guided by screws or pins 20 extending from frame 17 through slots 21, and each plate being yieldingly pressed downwardly by a spring 22 attached to frame 17 as by screws 23. All the ties engaged by carrier 9 are advanced one step each time the carrier moves forwardly a full stroke, and no tie returns with the rearward movement of the carrier. The advancing of the ties proceeds as follows: When carrier 9 is full of ties and in retracted position wire 3 is engaged in notches 24; wire 5 is engaged in notches 25; tie 26 at 12 is engaged in notches 27 of carrier extension and in notch 28 of side plates; and tie 29 is engaged by the front ends 30 of extensions 15 and in notches 31 of side plates 16. Now when carrier 9 is about to move forwardly binding-lever 8 rises to release wires 3 and 5 for forward movement. When carrier 9 moves forwardly, wires 26 and 29 push plates 16 upwardly by being pressed respectively against tapered surfaces 32 of notches 28 and against tapered surfaces 33 of notches 31. The forward movement of carrier 9 is arranged to place each tie in the place from which it has moved the preceding wire or tie, and tie 29 will have been moved to position 29', where it is held by extensions 34 provided on side plates 16. When the ties have been moved to these positions plates 16 and lever 8 drop, engaging the ties and wires in their notches and preventing them from being drawn rearwardly as the carrier 9 returns to original position. After each tie has been moved to position 29' and before another tie is moved to such position the stringing mechanism crosses two strings behind the tie near each end. Each succeeding tie arriving at position 29' moves the preceding tie ahead to position 29'', and the strings are crossed behind it, whereby the ties will be strung closely together in a strip, as shown at 35.

The means for crossing the strings behind each tie comprise two pairs of string-feeding levers having crossing movement, one pair on each side of the machine. Each pair of levers is arranged to make one crossing movement behind each tie. More particularly, on each side of the machine is a lever 36 having a hollow finger 37 extending inwardly behind a tie in position 29'. A string 38, feeding from a suitable reel or other source (not shown) is threaded through hollow finger 37. Also on each side of the machine is another lever 39 having a similar hollow finger 40 and string 41 threaded therethrough. Both levers 36 are keyed or otherwise fastened on a shaft 42

and are rigidly connected by a U-shaped link 43. Shaft 42 extends through sleeves 44 which are journaled in suitable bearings 45, and to the inner end of each sleeve 44 is keyed or otherwise connected one lever 39. These levers are also rigidly connected together by a rigid U-shaped link 46. At one side, shaft 42 and sleeve 44 extend beyond one bearing, and here to sleeve 44 is keyed or fastened a lever 47 and to shaft 42 is keyed or fastened a lever 48. In the present instance arm 47 extends upwardly and arm 48 extends downwardly. It is apparent that when arm 47 pivots rearwardly both stringing levers 39 rise above the tie at 29' to be tied, and when arm 47 pivots forwardly both stringing levers 39 fall below the tie at 29'. Similarly rearward movement of arm 48 lowers the stringing fingers of both levers 36, and forward movement of arm 48 raises these levers 36. To drive the stringing levers 36 and 39 so that each pair will cross once behind each tie positioned at 29' I provide a cam 49, geared as at 50 to the main driving shaft 51 of the tie-making machine 1, and associate with this cam 49 a cam roller 52 which is operatively connected with arm 47 by means of pin 53 and connecting rod 54, and also associate with cam 49 a cam roller 55 which is operatively connected with arm 48 by means of pin 56 and connecting rod 57. Pins 53 and 56 are slidably mounted in suitable slots 59 of a support or frame 58. Cam 49 is so shaped that as it rotates during the operation of the tie-making machine it will cause fingers 37 and 40 of levers 36 and 39 to cross each other once behind each tie after it arrives at position 29'. Thus during continued operation strings 38 and 41 on each side of the machine will be placed alternately under one tie and over the next tie, and whenever strings 38 go over a tie, strings 41 will go under a tie, and vice versa, thus weaving the ties securely together in the desired fashion. When a sufficient number of ties have been woven into a strip the strings 38 and 41 may be cut and a new strip started.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. For instance, it is obvious that this invention is not limited in its application solely to the manner of and machine for stringing stub-nosed or upset wire ties, which have been described merely as illustrative of this invention, but that this invention is broad enough to cover the stringing together of any other articles which are adapted to be strung together in the

manner of this invention but which heretofore have not been so strung together, and to machines and apparatus for mechanically securing, weaving, tying and binding together such articles in such manner. Also it is obvious that wire, tape or other binding material may be used instead of string, if desired.

What I claim is:—

1. In a device of the character described, in combination, a plurality of ties having upset ends, means for successively advancing said ties one at a time to a predetermined place, a plurality of strings arranged in pairs, and means for crossing each pair of strings behind each tie intermediate its upset ends when positioned in said place, to weave said ties into a strip-like package.

2. In a device of the character described, in combination, a plurality of ties having upset ends, means for successively advancing said ties one at a time to a predetermined place, a plurality of strings arranged in pairs, and stringing means for crossing each pair of strings behind each tie intermediate its upset ends when positioned in said place, to weave said ties into a strip-like package, said stringing means comprising oppositely operating levers each feedingly engaging one of said strings.

3. In a device of the character described, in combination, a plurality of ties having upset ends, means for successively advancing said ties one at a time to a predetermined place, a plurality of strings arranged in pairs, and means for crossing each pair of strings behind each tie intermediate its upset ends when positioned in said place, to weave said ties into a strip-like package, said stringing means comprising oppositely operating levers each feedingly engaging one of said strings, and driving means operating in synchronism with said advancing means and connections between said driving means and said levers for operating said levers.

4. In a device of the character described, in combination, a plurality of wire ties, mechanism, including a reciprocating carrier cooperating with a slidable plate, for successively advancing said ties to a certain place, a plurality of oscillating levers arranged in pairs, each lever having a finger

extending inwardly of said ties, a plurality of strings, one string associated with each finger and means for reversely oscillating the levers of each pair behind each tie when advanced to said certain place to cross the strings carried by each pair of levers once behind each tie.

5. In a device of the character described, in combination, a plurality of ties, means, including a reciprocating carrier cooperating with a slidable plate, for successively advancing each of said ties to a predetermined place, a plurality of strings arranged in pairs, and means for crossing each pair of strings behind each tie when positioned in said place, to weave said ties into a strip-like package, said stringing means comprising oppositely moving levers each feedingly engaging one of said strings, and driving means operating in synchronism with said advancing means and connections between said driving means and said levers for actuating said levers.

6. In a device of the character described, in combination, a plurality of wire ties, mechanism, including a notched reciprocating carrier cooperating with a notched vertically slidable plate, for successively advancing said ties to a certain place, a plurality of oscillating levers arranged in pairs, each lever having a finger extending inwardly of said ties, a plurality of strings, one string associated with each finger and means for reversely oscillating the levers of each pair behind each tie when advanced to said certain place to cross the strings carried by each pair of levers once behind each tie, said means, comprising a cam and operating mechanism therefor and connections between said cam and said levers.

7. In the art of packing wire ties, a package of ties comprising wire ties in parallel sidewise alignment, and binding strings extending along the line of ties and crossing between each two adjacent ties, binding the ties together, said ties having upset ends, whereby the ties are prevented from sliding endwise out of engagement with the binding material.

This specification signed this 21st day of October, 1922.

HENRY B. FOULDER.
